UNITED STATES PATENT OFFICE.

ELMER LEWIS GREENSFELDER, OF BALTIMORE, MARYLAND.

LOOSE-LEAF BINDER.

Application filed March 3, 1922. Serial No. 540,780.

To all whom it may concern:

Be it known that I, ELMER L. GREENSFELDER, a citizen of the United States, and resident of Baltimore, Maryland, have invented certain new and useful Improvements in Loose-Leaf Binders, of which the following is a specification.

My present invention relates to loose-leaf binders, rings and paper for same, the primary object being to produce a binder having distinct advantages over the usual binders now before the public.

It is well recognized that difficulty is experienced in removing sheets from and inserting them into loose-leaf binders of the "ring type" more particularly when a number of sheets are in the binder, and especially when the sheet or sheets being handled are at or near the top or bottom 20 of the pack of sheets.

This difficulty arises in a large degree from the fact that the rings of the binder open at or about the center, that is, the segments of the rings are of equal or about equal 25 length. I shall refer to such loose-leaf binders as "central opening binders". The gap in the open ring being centralized, it is considerably more convenient to insert a sheet in or remove it from the center or 30 near it than the top or bottom of the pack when the rings are filled or nearly filled to capacity, for at a point near or at the center, the segments of the open rings project far enough above the sheets to hold them in 35 position while a sheet is being removed or inserted. I shall henceforth refer to the sheet or sheets that are being removed or inserted as "active", and shall call those sheets "dead" which are to be held in position by the open segments of the rings while the active sheets are being handled. By "handling active sheets" I shall refer 40 to the process of either removing active sheets from or inserting them in the rings 45 of the binder.

In handling an active sheet in a binder of the usual central opening type, particularly when it is filled almost to or to capacity, it invariably happens when the active 50 sheet is located at or near the bottom or top of the sheets, that dead sheets, sometimes a number of them, come loose from their position and are forced above the open segments of the rings. This occasions considerable inconvenience, for these dead

sheets must be fitted back into position before the rings can be closed again.

It is obvious that such a difficulty should arise when the active sheet is near the top or bottom of the pack for then a much 60 larger number of dead sheets occupy the segments of one side of the binder than when the active sheet is near the middle of the pack.

To obviate such an objection, I have devised a form of binder, rings, and sheets which allow of ready and convenient handling of the active sheet or sheets at the end, near the end, and at central and other parts 65 of the pack while the dead sheets are held 70 in position.

In the drawings:—

Figure 1 is a plan view of a binder embodying my invention with rings open and 75 without a filler.

Fig. 2 is a view of a sheet which may be used with the device of Fig. 1.

Fig. 3 is a view similar to that of Fig. 1 with the binder loaded.

Fig. 4 is a plan view of the binder of Fig. 1 filled with sheets, all but one sheet being on the left of the rings.

Fig. 4^a is an end elevation of Fig. 4.

Fig. 5 is a perspective of a modification 85 having eccentric rings.

Fig. 6 shows two different combinations in a three-ring binder.

Fig. 7 illustrates a guide in connection 90 with a binder.

Fig. 8 is a detail of Fig. 7.

Referring now to these drawings, I have designated the binder or cover at 1, having the usual base 2 of any desired form which will hold the rings in either closed 95 or open position.

In Fig. 1 I have shown rings having separable segments of different lengths, for instance, segments 3^a, 4^a, 5^a, and 6^a are shorter than the complementary segments 3^b, 4^b, 5^b, and 6^b. It will be noted that rings 100 having segments 3^a, 3^b, and 4^a, 4^b have their segments opening to the left side of the top center and rings formed of segments 5^a, 5^b and 6^a, 6^b to the right thereof, each set of similarly opening rings preferably 105 having their openings in alignment.

The sheet used with such a device as shown in the above figures may be of the ordinary loose-leaf form, or as shown in Figs. 2 and 4, wherein holes are provided 110

in the same spaced relation as segments 5^a, 5^b and 6^a, 6^b, and slots or spaces 9 corresponding to segments 3^a, 3^b and 4^a, 4^b.

As the ordinary perforated loose-leaf sheet containing only holes to correspond with the rings adapts itself admirably to this binder, I prefer to use it in connection therewith. However, as the modified sheet containing perforations and slots or the like may in some instances be more convenient, I have illustrated this form exclusively as obviously wherever a slot occurs, a hole may be substituted.

In this form, reference being had to Fig. 3, it will be seen that on the right hand sheets, ring segments 5^a and 6^a pass through holes 8, and spaces 9 pass around or straddle ring segments 3^b and 4^b. This figure shows the binder opened at approximately the center of the pack of sheets. It will be seen that the sheets on the left of the rings are merely the sheets of Fig. 2 reversed or turned from those on the right. This causes holes 8 to engage segments 3^a and 4^a and spaces 9 to straddle segments 5^b and 6^b.

"Straddling" throughout this specification means where an aperture does not completely surround a ring or other holding means.

It will be seen that in the case of the sheet of Fig. 2, for a four-ring binder, two holes 8 and two spaces 9 are used. These spaces are preferably alternated with the holes as shown. I do not limit myself to the use of spaces and holes as specifically indicated by their shape in Fig. 2, this shape and arrangement merely being used in the diagrams accompanying these specifications as the best form for illustration.

A hole or slotted hole could be used instead of a space or slot, and in such a case the segment would pass through the hole instead of the paper straddling the segment. The size of the holes may of course vary as desired.

I do not limit myself to four rings, as more or less can be used and in such a case the same principle would be followed, additional or fewer holes and spaces being punched or placed in the paper accordingly.

It would be convenient to use one of the index markers near the center of the pack, say the letter M, as a dividing line. In this case all of the sheets from A to M inclusive

would be placed in the binder of Fig. 3 with the hole 8 uppermost. All of the sheets from N to Z inclusive would be placed in the binder of Fig. 3 with space 9 uppermost. Instead of using an index marker such as M for a dividing line, a specially colored or shaped sheet could be inserted at or about the center of the pack to serve as dividing guide, or a specially marked or colored tab attached to one of the central sheets could be used. When a new sheet is

to be inserted it would be placed in the binder with the hole 8 or space 9 uppermost, depending on which side of the dividing guide or marker it was to be entered. For example, in the case represented in Fig. 3, a sheet entered under an index letter in the first half of the alphabet would be placed in alphabetical position with the hole 8 uppermost, and a sheet entered under a letter in the latter half of the alphabet would be placed in alphabetical position with space 9 uppermost. If letter M did not represent the approximate middle of the pack, another letter which more nearly did could be chosen as the dividing line.

Figs. 4 and 4^a show the binder and rings filled almost to or to capacity the rings being open to handle an active sheet at the bottom of the pack. 10 represents the bottom sheet of the pack and 11 the dead sheets, which, in this case, are all on the same (the left) side of the binder. The segments 5^a and 6^a in this form though shorter than 5^b and 6^b, are amply long enough to pass through the holes of all the dead sheets below a central dividing line, or approximately one-half of the pack, and thus hold them in position. If 10 is not the very end sheet, that is, if there should be dead sheets below it, they are held in place by segments 5^a and 6^a which pass through the corresponding holes of these sheets. It is evident that the active sheet 10 can be readily removed from or inserted in the segments 5^a and 6^a. It is thus seen that the bottom or near bottom active sheet can be handled in a binder of this type well filled with paper while all the dead sheets are held in position, the lower sheets by short segments 3^a and 4^a, the upper ones by long segments 5^b and 6^b. Where it is desired to handle an active sheet at the top of the pack, the above operation is reversed.

An active sheet at or near the center, that is, at or near the dividing line, may be readily removed in the usual manner, the dead sheets still being held in position by segments.

It will be seen that in this form of sheet the holes and spaces are so punched and placed with respect to each other that the paper fits on the ring segments whether it is used in the normal position or upside down (reversed).

When the usual form of sheet having all holes and no spaces is used in my binder, no reversing of the sheets is necessary, and no central dividing line such as referred to is required. When such "all hole" sheets are used and the binder is open the long segments on both sides hold in position all sheets threaded over them as there are no sheets having spaces which merely straddle. The short segments obviously help to hold only those sheets in position through whose

holes they pass, while the longer segments serve to keep all dead sheets in position whether the pack is open at the top, center, or bottom.

5 It may be found that in certain forms of my binder where long segments are extra long that the sheet having holes and spaces can be placed into position over the proper segments more quickly than the sheet having all holes.

10 I do not limit myself to any one type or make of loose-leaf binder mechanism, the invention which I have described herein being applicable to practically all of the 15 ring loose-leaf binder and ledger mechanisms such as have been or are now before the public, whether the rings are opened and closed by merely pulling them apart, and pushing them together, or by lever, 20 spring, or other mechanism.

I do not wish to limit myself as to the best place to locate or best manner to group the holes and spaces, this being left to the judgment of the manufacturer of the binder, 25 as the best location and grouping may vary with binders of different shapes and dimensions, or binders for varying purposes. Alternation of spaces and holes is not absolutely essential.

30 Fig. 5 shows an arrangement of the rings, each set arranged eccentrically with respect to the other. The opening in this form of ring may be in any desired position.

The gap or distance between the ends of 35 the opened segments can be varied in length to best suit the purpose of the manufacturer, and similarly the point at which the union of the closed segments occurs may have various positions for various binders.

40 Fig. 6 shows diagrammatically two of the various combinations of central and non-central opening rings I may use in a three-ring binder. The sheets used with this form are preferably of the all-hole type.

45 It may be found desirable in some forms

of binder to provide guide means, shown at 24 in Fig. 7, which is a member suitably secured to the back or folder proper 1 in order to facilitate the holding of the dead sheets in position, more particularly where three or less rings are used.

The herein described invention enables the dead sheets to be held in position better and the active sheets to be handled better than in the case of the present style in use, 55 and also serves to increase the workable capacity of the binder, without increasing the sizes of the rings.

I have mentioned the longer segments as extending to one side of the top center, 60 meaning when the rings are closed, but in many instances it will be found desirable to have the long segment extend past the top center when the segments are separated, as this insures the dead sheets being held securely while handling active ones, as shown in Fig. 1, and therefore I do not wish to be limited to a construction wherein the long segment extends past the top center when the rings are closed or when open. 70

Having thus described my invention, what I claim is:

1. A binder of the type described, including a plurality of means having separable ends, adapted to receive sheets between their ends, the point of meeting of the ends of one of said means being out of alignment with the point of meeting of the ends of another means.

2. A binder of the type described, having a plurality of means for attaching a sheet to said binder, each of said means having separable ends, the point of meeting of said ends being to one side of the top center of said means, the point of meeting of the ends of two separate sheet-holding means being on opposite sides of the top center. 85

In testimony whereof I affix my signature.

ELMER LEWIS GREENSFELDER.
